BOTTOM MARGIN CONTROL FOR
TYPEWRITERS

Quang Hsi Hu and Chin Yi Lee, New York, N. Y.

Application October 27, 1949, Serial No. 123,838

5 Claims. (Cl. 197—141)

1

This invention relates to top and bottom margin control devices for typewriters.

This invention is a continuation of the invention set forth in our co-pending patent application, Serial No. 112,944, filed August 29, 1949, now Patent No. 2,535,539, issued December 26, 1950, wherein there is set forth a bottom margin control device which will automatically prevent the further typing upon a sheet disposed within the typewriter when a predetermined location has been reached at the bottom thereof.

It is an object of the present invention to make refinements upon the prior bottom margin control device wherein upon the setting of the drop arm upon the paper it is relative to the bottom edge of the paper and is not dependent upon the manner in which the paper is placed in the typewriter and wherein the drop arm and the support therefor is adjustable relative to the bottom edge of the paper, both being adjusted together and not as in the prior construction with the drop arm adjustable to the support and wherein the support does not need to be fixed or installed upon the typewriter chute.

It is another object of the present invention to provide on the support for the bottom of the paper sheet lined indications for any kind of spacing of typing, single, double or triple, so that the last line will exactly lie on the pre-set bottom margin, which is thus obtained precisely.

Other objects of the present invention are to provide a top and bottom margin control device for typewriters which is of simple construction, easy to operate and can be set by manipulation with two fingers, inexpensive to manufacture, self-contained and can be folded into a compact attachment, automatically controls the top margin along with the bottom margin, where the parts are so arranged that upon the return of the typewriter slide the impact at the end of the stroke will tend to be overcome by the angular movement of the parts of the arms to prevent the incidental disengagement or engagement of gears forming a part of the mechanism and efficient in operation.

For other objects and for a better understanding of the invention, reference may be had to the following detailed description taken in connection with the accompanying drawing, in which:

Fig. 1 is a side elevational view of the typewriter carriage and of the attachment embodying the features of the present invention with a paper sheet set in the typewriter carriage for operation.

Fig. 2 is a fragmentary plan view of the attachment.

2

Figs. 3, 4, 5 and 6 are respectively perspective views of the various parts of the adjusting arm and slide, Fig. 3 showing the slide and the finger, Fig. 4 showing the slide part containing the supporting arm, Fig. 5 showing the catch for the slides and Fig. 6 showing the spring for operating the catch.

Referring now to the figures, 1 represents a typewriter roll which is mounted for rotation in a carriage 3. Extending upwardly at the rear of the carriage is a paper chute or inclined support 4.

In front of the typewriter roll 1 is the standard press roll 5. Keys 6 are disposed in the usual position in front of the roll and below these keys is the usual guide rule 7. Paper 8 is fed from the inclined support downwardly through the carriage and over the roll 1. The bottom edge of the paper, at the beginning of the typing operation, extends upwardly from the typewriter chute 4. A frame 9 is secured to the carriage by screws 9a. A bracket 9b is fixed to the frame 9 by screws 9c and has an upwardly and rearwardly bent portion 9d.

A small gear 11 is fixed to the typewriter roll and a large gear 12 is caused to be slid into engagement with the gear 11 in the manner set forth in detail in the above mentioned co-pending application in order to effect the driving of an indicating disc 13 which is observed after the control device has been operated to let the operator know the number of spaces which can be made thereafter to bring the typing within the predetermined bottom margin for the paper sheet.

When the gear 12 starts to operate, tension spring 28 connected to post 14 on the disc 13 is stretched. A pointer 15 will give the indication on the disc 13. An adjustable stop lever 18 can be adjusted at any time to vary the margin width to be desired after or before the gear 12 has been put in mesh with gear 11.

A radially extending arm 16a on shaft 16 to which gear 12 is fixed is connected to an arm 19a of a rotatable structure 19. This structure 19 is rotatable in a supporting sleeve 20. The rotatable structure 19 comprises two parts pivotally connected together by a pin 19d so that the upper part can be folded down forwardly when the device is not in use. A slide 22 is adjustable upon the rotatable structure 19 and this slide has a handle 23. A spring 24 urges the rotation of the rotatable structure in a counter-clockwise direction, as viewed in Fig. 2, and causes the shifting of the shaft 16 inwardly, as viewed in Fig. 1. This spring 24 is connected

between the lower part of the structure 19 and the bracket sleeve 20. The slide 22 has a laterally extending finger 25 with a depending and enlarged ball-shaped engaging end 25a. The handle 23 is threaded upon the slide 22 and can be fixed to the rotatable structure 19 to hold the slide 22 against adjustment thereon.

The bottom edge of the paper sheet 8 at the beginning extends upwardly from the typewriter support 4 and is further supported by arm support 26. This arm support 26 has a fixed laterally extending member 27 and an adjustable part 27a pivotally connected at 27b to the laterally extending part 27 which is in turn fastened to slide block 36. It will be noted that this paper support 26 is not in any way attached to the paper chute 4 as in the prior construction.

The adjustable part 27a has different sets of indications. The indications 26a indicate the single spacings, the larger indications 26b indicate the double spacings, while the indications 26c at the opposite side of the part 27a give the triple space spacings. However, all indications, 26a, 26b and 26c are good for single spacing. The indications on the disc 13 of the lines left 25 will also be given in single, double and triple spacings.

The lower end of the paper support part 27a has a shape similar to a hook with a recess 26d over which the ball formation 25a of the finger 25 is supported when the paper is lying upon the paper support 26. The part 27 also has a recess underlying the recess 26d. As the bottom edge of the paper 8 passes downwardly under the ball 25a of the finger 25, the ball 25a will pass through the recesses to permit the rotation of the rotatable structure 19. This paper sheet 8 lies between the finger 25 and the support 26 to normally support finger 25 until the edge of the sheet is reached.

The outer end of the arm 27 is recessed, as indicated at 27c, to receive the hooked lower end of the adjustable supporting part 27a. The lower end of the part 27a has a straight edge 27d adapted to fit against the shoulder on the part 27 afforded by the recess 27c whereby to hold the part 27a in its vertically extended position. Below this straight edge 27d is a curved edge 27e and below this is a straight edge 27f. When the straight edge 27f engages the shoulder provided by the recess 27c of the part 27, the part 27a will be held in a horizontally extended position.

The arm 19a has a striker 19b which will strike bell 30 when the finger 25 is released from the bottom edge of the paper sheet 8. Guide plate 29 receives the tension spring 28 as the gear 12 and indicator disc 13 is rotated. The post 14 on the disc 13 will normally rest upon the frame stop block 33 and as disc 13 rotates it will come to rest against the adjustable stop 18a whereby to prevent any further rotation of the typewriter roll 1 and determine the bottom margin line to be made on the sheet. A hook 34 can be extended over a fixed sleeve 17 on the shaft 16 whereby to hold the gear 12 out of operation 65 when the device is not in use.

Pivottably adjustable about a pin 35b on the inclined portion 9d of the bracket 9b is an arm extension 35. The bracket arm 9d and the arm extension 35 are notched on the under sides, as indicated at 35a. When the device is not in use, the arm extension 35 can be pivoted forwardly about pivot pin 35b.

The paper support 26 further includes a slide block 36. This slide block has a recess 36a, Fig. 75

4, for receiving the bracket arm 9d and the arm extension 35 and to permit the adjustment of the slide block 36 thereover. The slide block 36 has upstanding extensions 36b and 36c receiving depending projections 22b and 22c of the slide 22. The depending projections 22b and 22c of the slide 22 can swing between the projections 36b and 36c which will permit the pivotable structure 19 to pivot in its sleeve support 20.

A retaining member 37 is pivotally connected to the lower end of the slide block 36 by a pin 38. This retaining element has at one end a projection 37b adapted to enter any one of the notches 35a on the bracket arm 9d and arm extension 35. The notches 35a are disposed one quarter of an inch apart. A retaining spring 39 of U-shape is disposed in one end of the retaining element 37 and is so shaped and constructed as to keep the retaining element 39 pivoted to urge the projection 37b toward the notches 35a. The spring 39 will lie within the upstanding portion 37c of the retaining element.

The paper support 26 being connected with the slide block 36 and the slide block being connected with the slide 22 for adjusting the finger 25, both the paper support 26 and the finger 25 will be accordingly adjusted together when making the settings for the different margins to be left at the bottom of the sheets. The paper support 26 will be adjusted to the different distances on the bracket arm 9d and the arm extension 35.

By grasping the handle 23 and pivoting the slide 22, the finger 25 can be lifted. To move the slides, the operator depresses the retaining element 37 to disengage the tooth projection 37b from the notch. She will then move the whole assembly along the arm 35 to the desired bottom margin setting. She then releases the retaining element to fix the assembly in the adjusted position and to re-engage the projection 37b into one of the notches 35a. The handle 23 can be tightened, if necessary, to fix the slide 22 to the pivotable structure 19.

The successive paper sheets of the same size, when inserted, can be easily brought to the same top margin by observing the location of the bottom edge upon the indications on part 27a to start typing each time. To be certain that the last line will fall at exactly the preset margin, the bottom edge of the paper sheet is placed in line with the indications 26a, 26b or 26c depending on whether single, double or triple spacings are to be used.

With the paper support 26 being adjustable with the finger 25 and with the bottom edge being aligned with the indications on part 27a, the bottom margin is accurately obtained and the last typed line will exactly lie at the preset distance from the bottom edge. The last line will fall exactly at the preset margin for any kind of typing spacing. The finger 25 will be well supported up to the edge of the sheet and upon being released will move gear 12 into engagement with gear 11 so that the disc 13 with the stop post 14 thereon is rotated until the post 14 comes into engagement with the adjustable stop lever 18. At that time, further movement of the roller is positively prevented.

If the paper support part 27a is angularly adjusted relative to the part 27, the finger 25 will be supported on the support 26 and keeps the device from functioning. The pivotable structure 19 has its mass so distributed that it will tend to keep the gears 11 and 12 in mesh as the

typewriter carriage is jolted at the ends of its travel.

While various changes may be made in the detail construction, it shall be understood that such changes shall be within the spirit and scope of the present invention as defined by the appended claims.

What is claimed is:

1. In combination, a typewriter carriage, a typing roll rotatable upon the carriage, said typing roll being adapted to receive a paper sheet, a bottom margin control device mounted on the carriage and associated with the typing roll to stop the rotation of the same upon the predetermined bottom margin of the paper sheet being reached, said bottom margin control device including a support mounted on one end of the carriage, an adjustable paper supporting arm extending laterally upon the support and vertically adjustable thereupon for supporting the bottom of the paper sheet and a trip finger pivotally carried upon the support and associated with said paper supporting arm for release upon the paper bottom edge passing from the paper supporting arm, said trip finger serving to put into operation the device to stop rotation of the typing roll, said supporting arm having single, double and triple space indications on which the bottom edge of the paper sheet may be placed to start typing whereby to make certain that the last line will fall exactly at the preset bottom margin.

2. In combination, a typewriter carriage, a typing roll rotatable upon the carriage, said typing roll being adapted to receive a paper sheet, a bottom margin control device mounted upon the carriage and associated with the typing roll to stop the rotation of the same upon the pre-selected bottom margin of the paper sheet being reached, said bottom margin control device including a frame connected to the carriage, normally fixed elements on the frame adapted to be driven when released after a predetermined number of spacings of the typing roll to cause the typing roll to be stopped, a pivotal structure extending upwardly from the frame and operable upon the elements to release them and to initiate their action including arm means extending upwardly from the frame and pivotal thereon, a slide with a finger thereon adjustable on said pivotal arm means, fixed arm means extending upwardly from the frame, a slide block adjustable upon the fixed arm means, said slide block having a paper supporting arm thereon,

said slide block being adjustable to permit the release of the finger of the pivotal arm means at different distances from the line of typing of the paper sheet, said finger adapted to rest on the paper sheet and adapted to drop from the bottom edge of the paper sheet through the paper supporting arm upon the paper sheet having moved from under the finger.

3. The combination as defined in claim 2, said 10 fixed arm means for the slide block having a plurality of spaced notches, a retaining element adjustable upon the slide block and having a projection adapted to engage any one of the notches on the arm means whereby to retain the slide block in its adjusted position thereupon, said slide upon the pivotal arm means engaging with the slide block to be adjusted therewith.

4. The combination as defined in claim 2, 15 said slide block being releasably retained upon the fixed arm means, said slide upon the pivotal arm means having portions engageable with the slide block on the fixed arm means to permit the pivotal movement of the pivotal arm means, but allowing the slide to be adjusted 20 upon the pivotal arm means as the slide block is adjusted upon the fixed arm means for the different margin settings, said pivotal arm means having an arm extension which can be pivoted forwardly to an out-of-use position, said 25 finger slide being adjustable upon the arm extension and releasable from the slide block of the fixed arm means when the arm extension of the pivotal arm means is moved to the out-of-use position, and a handle screw adjustable upon 30 the slide to fix the slide to the arm extension.

5. The combination as defined in claim 2, said 35 paper supporting arm comprising a laterally-extending part connected to the slide block on the fixed arm means, an adjustable supporting 40 part pivotally connected to the laterally-extending part to be adjusted between vertical and horizontal positions, said parts having recesses 45 which are aligned when the adjustable part is in the vertically extending position, said finger adapted to pass through the aligned recesses of 50 said part upon the paper sheet being drawn from under the finger, the adjustable part upon being adjusted to its out-of-use position to place the recesses of the parts out of alignment and to cause the finger to be supported by the parts.
